United States Patent Office.

ALBERT H. GILMAN, OF HOPEDALE, MASSACHUSETTS.

Letters Patent No. 66,017, dated June 25, 1867.

IMPROVEMENT IN SPINDLES FOR SPINNING.

The Schedule referred to in these Letters Patent and making part of the same.

TO ALL PERSONS TO WHOM THESE PRESENTS SHALL COME:

Be it known that I, ALBERT H. GILMAN, of Hopedale, in the county of Worcester, and State of Massachusetts, have made a new and useful invention having reference to Spinning-Spindles and the caps of their steps; and I do hereby declare the same to be fully described in the following specification and represented in the accompanying drawings, of which—

Figure 1 is an elevation; and

Figure 2, a longitudinal section of a spindle, its step and cap provided with my invention.

The nature of my invention consists in the application of the step-cap or cover to the spindle by means or devices such as, when the cap may be encompassing or covering the step and the spindle may be in revolution, shall not only cause the cap to be revolved with the spindle, but allow it, the said cap, to be freely raised off the step in order to enable such step to be supplied with oil, as occasion may require. It further consists in the combination and arrangement of a collar with the spindle and the cap, to be arranged with a step, as set forth. It further consists in the arrangement of a collar and a stud with the spindle and cap provided with a recess to receive the stud and to be applied to a step, as hereinafter explained. The objects of my invention are to enable the cap to be raised off the step in order that the latter may be supplied with oil while the spindle may be in revolution; also, to prevent dirt and waste that may work down between the cap and the spindle from dropping into the step.

In the drawings, A denotes the spindle; B its step; a the bushing of the step; b the point of the spindle, and C the cap of the step. The cap encompasses the spindle and slides freely up and down thereon. When down to its lowest position it encircles and covers the upper part of the step and rests on a collar or annulus, D, fixed on the spindle concentrically, and having a diameter equal or about equal to that of the larger part of the bore of the cap. A hole, c, is bored vertically in the cap to receive a pin or stud, d, extending upward from the collar. The purpose of the stud and hole is to so clutch the cap to the spindle when the cap is resting on the collar that the cap will revolve with the spindle. As a substitute for the stud and hole, a leather washer, placed on the collar and around the spindle, could be used, but not to so good advantage. The collar, besides serving as a support for the cap, answers as a protector of the step against dust, waste, or extraneous matters, such as are liable to work down between the cap and the spindle when they are in use, and the former is so applied to the latter as to be capable of being freely moved up and down thereon. In the common application of the cap to the spindle the former is fastened to the latter by means of a screw or otherwise, so that while the spindle may be in revolution the cap cannot be raised thereon in order to allow oil to be poured into the step, but with my invention or improvement the cap can be raised while the spindle may be in rotation, and on being dropped down to its position to cover the step will revolve with and be revolved by the spindle. Even were the cap to rest on the step and not rotate with the spindle the collar D will still serve as a protection to the step, and in manner as hereinafter explained.

I claim as my invention the following, that is to say—

I claim the application of the step-cap C to the spindle A by means or devices such as, when the cap may be encompassing or covering the step, and the spindle may be in revolution, shall not only cause the cap to be revolved with the spindle, but allow it, the said cap, to be freely raised off the step in order to enable such step to be supplied with oil as occasion may require.

I also claim the combination and arrangement of the collar D with the spindle A and the cap, arranged with a step, as set forth, the collar being for the purpose or objects as explained.

I also claim the arrangement of the collar D and the stud d with the spindle A and the cap C, provided with a recess or hole, c, to receive the stud, and applied to a step, B, substantially as described.

ALBERT H. GILMAN.
